UNITED STATES PATENT OFFICE.

DEAN HARPER THOMPSON, OF LODI, CALIFORNIA.

PUMP.

Application filed April 4, 1921. Serial No. 452,970.

To all whom it may concern:

Be it known that I, DEAN HARPER THOMPSON, a citizen of the United States, and resident of Lodi, county of San Joaquin and State of California, have invented a new and useful Pump, of which the following is a specification.

The present invention relates to improvements in pumps and its object is to provide a positive acting, continuously operating, combined suction and pressure pump having a continuous suction and discharge that is economical, simple and substantially built.

15 I accomplish this object by means of the mechanism illustrated in the accompanying drawing, in which Figure 1 represents a longitudinal vertical section through my pump, Figure 2 a horizontal section through the same, substantially along line 2—2 of Figure 4, Figure 3 an inside view of one of two rotary wheels used in my pump, Figure 4 a transverse vertical section along line 4—4 of Figure 1, Figure 5 a side view of the 20 pump with a cover and a rotating wheel removed, and Figure 6 a perspective view of one of the rotary wheels of my pump.

Referring to the drawings more particularly it will be seen that the housing (1) 25 supports in two roller bearings (2) the shaft (3), which is rotated by means of any suitable power actuating the pulley (4). The housing consists of a rigid central part (6) provided with two circular parallel faces or flanges (7) and two covers (8), the flanges (9) of which are bolted to the circular parallel faces or flanges (7) of the housing as shown at (11). Inside of the covers (8) the shaft carries two symmetrical rotary 30 disks or wheels (12), one on either side of the parallel flanged faces of the housing. These two disks or wheels are keyed to the shaft so as to rotate with the same and are firmly pressed against the parallel flanged 35 faces of the housing by means of two large nuts (14) engaging threaded parts (16) of the shaft. Ball-thrust bearings (17) are provided to reduce the friction between the disks or wheels and the central part of the 40 housing, and packing rings (18) serve to prevent any air or liquid from leaking through between the disks or wheels and the parallel faces of the housing, springs (19) tending to give a certain elasticity to 45 said packing rings.

The two disks or wheels (12), shown par-

ticularly well in Figures 1, 2, 3 and 6, are of solid cross-section but have, on their inner surfaces, pockets or chambers (23) cut into the same, two bounding surfaces (20) of which are semi-circular in outline and concentric with the axis, while the two other bounding surfaces (22) are in radial planes and sloping in cross-section. They are arranged on the shaft in such a manner that their inner faces run parallel and that at all times the semi-circular chamber or pocket in one disk or wheel is opposite the solid portion of the opposite disk or wheel and vice versa, and are designed to alternately register with the openings (25) through the parallel flanged faces of the housing which terminate into the suction and discharge openings (26) and (27).

It will be seen that the central part of the housing, which may be called the stator of my pump, provides inside space only above the shaft (3), the lower part consisting of supports only. This inside space is provided with the inlet pipe (26) and the discharge pipe (27), the two pipes being arranged opposite of each other and being separated from each other by a movable partition or plunger (28) extending longitudinally through the stator and dividing its inside space into two compartments (29) and (31). This movable partition or plunger (28) is composed of a series of plates (32) lying flat against each other. The two outside plates are solid, while all the inner plates are perforated in such a manner that none of the perforations register with those of the adjoining plates. These perforations serve as carriers of grease admitted between the plates through the grease cup (30) and tend to reduce the friction between the plates by reducing the area of surfaces in contact. These plates, as shown in Figure 4, are held in place by two upper guides (33) and two lower guides (34) and are capable of longitudinal movement only. Longitudinally they extend from the inside face of one disk or wheel to the face of the solid portion of the opposite disk or wheel and, since the distance between the two faces remains constant throughout the rotation, the movable partition or plunger will always maintain a liquid or air-tight connection with the faces of the disks or wheels. Likewise, since the top and bottom surfaces of the movable partition or plunger come in direct contact with the horizontal surfaces

of the semicircular chamber or pockets it will be seen that no air or liquid can pass the movable partition or plunger in either direction at any period of the rotation of 5 the disks or wheels.

Having thus described the essential features, elements, and the co-relations there-between, like reference characters being utilized to indicate similar features and elements throughout, the operation of the 10 pump is set forth as follows:

Since the movable partition or plunger (28) is of a length equal to the distance between the inner face of the semi-circular chamber (23) in one of the disks or wheels 15 (12) and the solid face of the opposite disk or wheel, and as will be observed, the radial sides (22) of these chambers present an inclined surface to the ends of the movable 20 partition or plunger (28), it will be clearly evident that with every revolution of the disks or wheels (12), the movable partition or plunger (28) will be reciprocated transversely of the housing (6), alternately entering 25 first one and then the other semi-circular chamber, which it divides into two parts. Since the volume of the semi-circular chambers will increase on one side of the movable partition or plunger (28) proportionately to the decrease in volume of the 30 opposite side, it will be clearly evident that the tendency to create a vacuum between the receding end of the semi-circular chamber and the movable partition or plunger will 35 cause that chamber to become filled with air or liquid through the openings in the parallel faces (7) of the housing (6) leading to the chamber (29) and the suction pipe (26), while the approaching end of the same 40 semi-circular chamber on the opposite side of the movable partition or plunger will empty the chamber of its contents (with which it was filled on the preceding revolution) by forcing it out through the opening 45 in the parallel face (7) of the housing (6) into the chamber (31) and the discharge pipe (27). Thus the semi-circular chambers in each disk or wheel will be filling and emptying simultaneously in each revolution 50 and as this operation takes place alternately it will be clearly evident that the action of 55 the pump will be continuous both in suction as well as discharge and since this action is positive in nature, the capacity of the pump as well as the pressure which it exerts upon the discharging contents will be contingent 60 only upon the speed at which the pump is driven or the power exerted in operating.

I claim:

1. In a pump, a housing having a shaft 65 rotatably mounted therein, two wheels hav-

ing inwardly facing chambers of semi-circular contour and sloping radial sides keyed to said shaft so that their inner surfaces are parallel, and a partition supported in said 65 housing extending between said two wheels, said partition being longitudinally divided into sheets movable independently of each other, and an inlet and a discharge arranged on opposite sides of said partition. 70

2. In a pump, a housing having a shaft rotatably mounted therein, two wheels having inwardly facing chambers of semi-circular contour and sloping radial sides keyed to 75 said shaft so that their inner surfaces are parallel, and a partition supported in said housing extending between said two wheels, said partition being longitudinally divided into a plurality of sheets movable independently of each other, the two outside sheets 80 being solid, the inside sheets being perforated and an inlet and a discharge arranged on opposite sides of said partition.

3. In a pump, a housing having a shaft rotatably mounted therein, two wheels having inwardly facing chambers of semi-circular contour and sloping radial sides keyed to 85 said shaft so that their inner surfaces are parallel, and a partition supported in said housing extending between said two wheels, 90 said partition being longitudinally divided into a plurality of sheets movable independently of each other, the two outside sheets being solid, the inside sheets being perforated, said perforations being adapted to receive and to distribute a lubricant between the several sheets. 95

4. In a pump, in means for providing a stationary liquid-and air-tight connection between two rotating wheels having parallel, but uneven surfaces, a partition longitudinally divided into a plurality of sheets movable independently of each other. 100

5. In a pump, in means for providing a stationary liquid- and air-tight connection 105 between two rotating wheels having parallel, but uneven surfaces, a partition longitudinally divided into a plurality of sheets movable independently of each other, the two outside sheets being solid, the inside 110 sheets being perforated.

6. In a pump, in means for providing a stationary liquid- and air-tight connection between two rotating wheels having parallel, but uneven surfaces, a partition longitudinally divided into a plurality of sheets movable independently of each other, the two outside sheets being solid, the inside sheets being perforated, said perforations being adapted to receive and to distribute a 115 lubricant between the several sheets. 120

DEAN HARPER THOMPSON.
